LLP(57) **CLAIM**

The ornamental design for a payment terminal, as shown and described.

DESCRIPTION

FIG. 1 is a perspective view of an embodiment of a payment terminal showing the new design;

FIG. 2 is a front view of the embodiment of FIG. 1;

FIG. 3 is a bottom view of the embodiment of FIG. 1;

FIG. 4 is a right side view of the embodiment of FIG. 1;

FIG. 5 is a left side view of the embodiment of FIG. 1;

FIG. 6 is a top view of the embodiment of FIG. 1; and,

FIG. 7 is a rear view of the embodiment of FIG. 1.

Broken lines in the drawings depict portions of the payment terminal that form no part of the design to be patented.
